UNITED STATES PATENT OFFICE.

HOWARD A. HANDS, OF WATERTOWN, MASSACHUSETTS, ASSIGNOR TO HOOD RUBBER COMPANY, OF WATERTOWN, MASSACHUSETTS, A CORPORATION OF MASSACHUSETTS.

MULTIPLE-HEATER CONTROL.

Application filed June 17, 1926. Serial No. 116,652.

My present invention relates to improved means for regulating the temperature of a plurality of electric heaters and aims to provide relatively simple, economical and efficient means whereby the temperature of said heaters may be regulated by a single control instrument operating on said heaters in succession.

The invention includes the novel construction and arrangement and combination of parts hereinafter described, the precise nature and scope of the invention being defined by the appended claims.

In order that the invention may be more readily understood, reference is made to the accompanying drawings in which:

Figure 1 is a diagrammatic view.

Fig. 2 is a sectional elevation.

Fig. 3 is a detail view of the depressor bar and associated circuit closing parts.

Fig. 4 is an enlarged detail view of the drum as seen in elevation.

Fig. 5 is a detail plan view of the adjustable cam plates as viewed from above Fig. 4.

Fig. 6 is a sectional detail on a larger scale to illustrate the cooperation of contact finger and drum strip.

Fig. 7 is a diagrammatic detail.

Fig. 8 is a front elevation of a modified form of the invention embodied in apparatus for multiple control, parts being broken away and parts omitted for sake of illustration.

Fig. 9 is a side elevation of the apparatus of Fig. 8 with parts in section.

Fig. 10 is an enlarged detail section of one of the fixed discs for the distributor contacts, and

Fig. 11 is a fragmental face view of the parts of Fig. 10.

Referring by reference characters to this drawing, Fig. 1, it is assumed that there is a group of heaters, four being shown by way of example, and the position of which is indicated conventionally at 76, 76^a, 76^b and 76^c, and in which the temperatures are to be controlled automatically from a single control instrument, so designated on the drawing.

Associated with each heater is a thermo-couple, these being designated 35, 35^a, 35^b and 35^c respectively, and while they are shown apart from the heaters for convenience in tracing the circuits, it will be un-

derstood that in practice they are incorporated in the heaters, or associated apparatus so as to be affected by the temperature thereof.

The thermo-couples are electrically connected to a control instrument (so designated in the drawing) embodying a galvanometer needle G (Figs. 2 and 3) having circuit closing means associated therewith and adapted to be positioned by the movement thereof, to cooperate with switch contacts *h*, *c* and *l* of the line connections marked H, C and L, and standing respectively for high, common, and low. The circuit closing is effected by a depressor bar 100 operative throughout the range of movement of the needle and which depressor bar may be operated intermittently in any suitable manner, but preferably by a solenoid, or magnet, as indicated at 74. The needle G carries a projection *g* designed to engage one or the other of a pair of spring arms *h'* and *l'* electrically connected with the lines H and L respectively and which arms respectively carry the contacts *h* and *l* which, when depressed, engage selectively the opposed contacts *c* which are both electrically connected to the common line C.

A bridge piece 101° of inverted wedge shape serves to deflect the needle to one side or the other (Fig. 3) if the depressor bar should be lowered when the needle is directly opposite the space between the ends of the spring arms *h'* and *l'*. It will be understood that if the temperature of the furnace is below the predetermined limit the galvanometer needle will be in such position that the action of the depressor bar will so control the circuits as to turn on the heat, while if above a predetermined limit, the heat will be cut off, this operation broadly being well understood by those skilled in the art.

This is effected in the present instance by electrically connecting the H and L contacts with the conductors 15 and 16 respectively of the power line (here indicated for example as a 110 volt A C line, Fig. 1) and the C contact to relays or "contactors" comprising solenoids 11, 11^a, 11^b or 11^c, one for each furnace, each of which when energized closes switches or contacts 12, 12^a, 12^b or 12^c, and also the control switches or contacts 13, 13^a, 13^b, or 13^c, see Fig. 7.

The heaters are connected to the power

line through the main contacts 12, 12^a, 12^b, and 12^c, while in series with each set of control contacts 13, 13^a, 13^b and 13^c, is a resistor 14 of predetermined value.

5 In order to make the one control instrument effective to control a plurality of heaters, I provide circuit controlling means which I prefer to construct in the shape of a cylindrical drum 36 of insulating material 10 and of suitable dimensions, driven at slow speed through suitable connections by a motor 37 (see Fig. 4), electrically connected to the power line and controlled by switch 26.

15 On the drum are three sets of contacts with co-operating contact fingers (such as 19, Fig. 5), one set #1 (Fig. 1) effecting the change of thermo couples, another set #3 the change of relays 11, while the remaining 20 set #2 controls a circuit through the solenoid 74 which operates the depressor bar.

Set #1 consists of one strip of brass or other conducting strip 38, extending completely around the drum, and four others 25 39, 40, 41, and 42, each covering only one-quarter of the periphery, all in separate paths. Set #2 consists likewise of a conductor strip 43 extending completely around the drum, and four others 44, each covering 30 perhaps one-twentieth of the periphery. These last four 44, are all in the same path. Set #3 is similar to set #1, having the strip 20 all around with four other contacts, 22, 45, 46 and 47, all in different paths, but each 35 of the last four, 22, 45, 46 and 47, covers only say one-thirtieth of the periphery. To engage with these twelve strips are twelve flexible contact fingers 19, 23 and 48 to 57 inclusive, mounted on the framework of the 40 instrument. Contacts 39 to 42 inclusive are permanently connected to contact 38 by connectors 58 to 61 inclusive; 44 to 43 by connectors 62, and 22, 45, 46 and 47 by connectors 21, 63, 64 and 65, respectively.

45 Starting with everything cold, snap-switch 26 is turned on. Motor 37 starts to rotate drum 36. Contacts 48, 53 and 19 are in contact with the full length strip contacts 38, 43 and 20 respectively, and finger contact 49 is in contact with strip contact 39. This completes a circuit through 35, 66, 49, 39, 58, 38, 48, 70, through the galvanometer of the control instrument, and wire 71 back to the thermocouple. As the thermocouple 50 is cold, no current will flow in this circuit and the galvanometer needle will remain at the lower end of the scale. After a short interval of time, the turning of the drum 36 brings contacts 44 and 54 together, completing a circuit from line 15 through 72, 53, 43, 62, 44, 54, 73, solenoid 74, and wire 75, back to line 16. Energizing the solenoid 60 lowers the depressor bar and causes the low contacts "L" and "C" (under present condition) to momentarily close. A further

slight turn of drum 36 brings contacts 22 and 23 together, completing a circuit from line 16 through 17, "L", "C", 18, 19, 20, 21, 22, 23, 24, 11, 25, 26, and 27 to line 15. This energizes solenoid 11, causing its armature 70 to close contacts 12 and 13. Closing contacts 12 completed the circuit of heater 76 from line 15 through 32 to heater 76 thence through wire 33, closed contacts 12, wires 34, 29 and 30 to line 16. The simultaneous 75 closing of contacts 13 completes a circuit from line 16 through 30, 29, 14, 13 and 28 to the solenoid 11, a path in parallel with the circuit through the instrument contacts "L" and "C". Heater 76 is now on and thermo-couple 35, associated with it, begins to heat up.

Further rotation of the drum opens contact connections between 49 and 39, 54 and 44, 23 and 22, allowing the depressor bar to 80 rise, and opening the circuit through "L" and "C". Solenoid 11 still remains energized, however, through the parallel path through contacts 13, and the power stays on heater 76.

Coincident with the breaking of these circuits, another circuit is made through finger contact 50 and strip contact 40, completing a circuit through thermocouple 35^a and the galvanometer of the control instrument. 85 The cycle described above is gone through again, until at its completion heater 76^a is on the line. In like manner 76^b and 76^c are connected to the line as drum 36 continues to revolve.

100 After one complete rotation of the drum, thermocouple 35 is again connected to the galvanometer through contacts 39 and 49. Its temperature has supposedly risen by this time, but it may or may not be as high as the temperature for which the control instrument is set. If it is not, nothing changes. The depressor bar drops, finds the pointer still on the low side of the setting, closing contacts "L" and "C", which simply complete a circuit in parallel with one already existing through contacts 13.

110 This condition exists for all couples and heaters until the temperature at one of the couples rises above the desired point. Assume that this condition exists when contact 39 reaches contact 49 on a certain rotation. The current through the circuit then, due to the excess temperature of couple 35, causes the galvanometer needle to go beyond the 115 temperature setting. Upon the closing of the contacts 44 and 54, the depressor bar finds the needle on the high side and consequently closes the high contacts "H" and "C". This sets the stage for the completion of a circuit from line 15 through 31, "H", "C", 18, 19, 20, 21, 22, 23, 24, 28, 13, 14, 29 and 30 to line 16 as soon as the contacts 22 and 23 are closed. This shorts out solenoid 120 11, contacts 12 and 13 open, and both heater 125 contacts "L" and "C" closed. This completes the cycle.

76 circuit and the control circuit through 13 are opened. The temperature of heater 76 then begins to fall.

Thus the various cycles go on, with a 5 heater circuit being opened or closed according to whether its associated couple indicates a temperature higher or lower than that desired, and thus the temperature of all four heaters are kept within a reasonable 10 range of the temperature desired.

It is frequently desirable that different 15 heaters shall be capable of being set to operate at different temperatures and I have accordingly provided means by which any given heater may be set for any desired 20 temperature without otherwise affecting the action of the control instrument. To this end the H, C and L contacts are carried by a post 101 having its lower end secured 25 to the outer end of a swinging arm 102, fast on the upper end of a shaft 103 in axial alignment with the axis of the galvanometer needle. This shaft carries an arm 104 provided at its free end with a roller 104^a 30 adapted to coact with a series of contact plates 105 adjustably secured to a disc 106 fixedly attached to the upper end of the drum 36 or its shaft. Each of these plates 35 105 has an outer edge concentric with the axis of the drum and it is made radially adjustable of the carrying plate 106 by means such as slots and clamp screws as shown in Fig. 6. A spring 107 tends to 40 rotate the shaft 103 to keep the roller 104^a in contact with the peripheries of plates 105. There being one plate for each heater it will be seen that the position of the corresponding plate, to wit, the amount of its radial adjustment, will determine the temperature of its respective heater due to the 45 angular adjustment of arm 102 carrying the control contacts.

The invention is capable of use for the control of a very large number of heaters in which event I prefer to modify the distributor mechanism as shown for example in Figures 8 to 11 inclusive.

In this I have shown the distributor contacts corresponding to sets 1 and 3 of the 50 first form described above as carried by fixed discs 110, 110^a, the cooperating contacts or brushes (corresponding to 19 Fig. 5) being carried by arms 111 fast on a shaft 112 driven by suitable gearing from a motor 55 113 through the intermediary of a suitable speed transformer 114. In this form I have shown the depressor bar as mechanically operated (instead of electrically) this being effected by a cam disc 115 co-operating with 60 and actuating the plunger rods 116 which in turn actuates the depressor bar in a manner similar to that disclosed in Fig. 2. Cam disc 115 is fast on a shaft 117 driven by chain and sprocket gearing from shaft 112.

65 The adjustable temperature controlling discs

(corresponding to 105 of the first form) are shown at 118 carried on the periphery of a drum 119 fast on a shaft 120 driven by chain and sprocket gearing from shaft 117.

In this embodiment I have shown the 70 drums as provided with plates or cams for the control of temperature of fifteen heaters. The plates are secured to the periphery of the drum by clamp screws 118^a passing through elongated openings in the plates and 75 adjusting screws 118^b serve for accurate adjustment when the clamp screws are loosened.

In Figures 8 to 11 the circuits are omitted for simplification of illustration as the manner of providing these would be obvious to one skilled in the art in view of the disclosure in connection with Figs. 1 to 7.

As indicated in Fig. 8 the shafts 112, 117 and 120 may be of such length as to 80 provide for the control of a plurality of groups of heaters.

By this arrangement a very large number of heaters may be controlled as to temperature from a single control station. 85

Having thus described my invention, what I claim is:

1. In an automatic temperature regulator for a plurality of electric heaters, a plurality of thermo electric elements associated with said heaters, a plurality of circuit controllers for regulating the current supplied to said heaters, a single control instrument adapted to be influenced by one or another of said thermo electric elements, and a common distributor with switches and connections whereby the single control instrument is placed in operative relation with one or another of said thermo electric elements and with the corresponding circuit controllers. 100 105

2. In an automatic temperature regulator for a plurality of electric heaters, a plurality of thermo electric elements associated with said heaters, a plurality of circuit controllers for regulating the current supplied to said heaters, a single control instrument adapted to be influenced by one or another of said thermo electric elements, means associated with said control instrument for determining the temperature of any given heater, and a common distributor with switches and connections whereby the single control instrument is placed in operative relation with one or another of said thermo electric elements and with the corresponding circuit controllers. 110 115 120

3. In a control system, the combination of a plurality of heaters, a single electrical instrument adapted to be successively controlled by the temperature of said heaters, and comprising a pointer and means for controlling said heaters including two electric circuits having movable terminals separate from but dependent upon said pointer, 125 130

- means for periodically causing said pointer to selectively actuate said terminals to close said circuits, and means for automatically moving said terminals to a predetermined 5 position relative to any particular heater.
4. In a control system, a plurality of electric heaters, a plurality of thermo electric elements associated with said heaters, a plurality of circuit controllers for regulating 10 the current supplied to said heaters, a single control instrument adapted to be influenced by one or another of said thermo electric elements, and comprising a pointer and means for governing the action of said circuit closers including two electric circuits having movable terminals spaced from but dependent upon said pointer to selectively actuate said terminals, means for periodically actuating said pointer to close one or 15 20 the other of said circuits, a continuously driven common distributor with switches and connections whereby the single control instrument is placed successively in operative relation with said thermo electric elements and the corresponding circuit closers, and a member moving in unison with said distributor and having individually adjustable parts corresponding in number to said heaters, and means whereby said individual parts control the position of said terminals.
5. In a control system, a plurality of electric heaters, a plurality of thermo electric elements associated with said heaters, a plurality of circuit controllers for regulating 30 the current supplied to said heaters, a single control instrument adapted to be influenced by one or another of said thermo electric elements and comprising a pointer, and means for governing the action of said circuit closers including two electric circuits having movable terminals spaced from but dependent upon said pointer to selectively actuate said terminals, means for periodically actuating said pointer to close one or 35 40 the other of said circuits, a continuously driven common distributor with switches and connections whereby the single control instrument is placed successively in operative relation with said thermo electric elements and the corresponding circuit closers, said terminals being mounted for bodily movement in a path concentric to the axis of said pointer, and means for bodily moving 45 50 55 said terminals comprising a rotary member having adjustable contact elements corresponding in number to the number of heaters, and a cooperating contact member having operative connection with said terminals.
6. An automatic temperature regulator according to claim 1 in which the distributor comprises a fixed disc or, discs carry-
- ing one set of contacts and the cooperating contacts are carried by a swing arm fast on a motor driven shaft.
7. An automatic temperature regulator according to claim 1 in which the distributor comprises a fixed disc or discs carrying one set of contacts and the cooperating contacts are carried by a swing arm fast on a motor driven shaft, and the depressor bar of the control instrument is operated by a rotary cam carried by a shaft driven from the aforesaid shaft.
8. An automatic temperature regulator according to claim 1 in which the distributor comprises a fixed disc or discs carrying one set of contacts and the cooperating contacts are carried by a swing arm fast on a motor driven shaft, and the depressor bar of the control instrument is operated by a rotary cam carried by a shaft driven from the aforesaid shaft, and in which the terminals of the control elements carried on the periphery of a drum mounted on a shaft driven from the shaft carrying the depressor bar actuating cam.
9. In an automatic temperature regulator for a plurality of electric heaters, a plurality of thermo-electric elements associated with said heaters, a plurality of circuit controllers for regulating the current supplied to said heaters, a single control instrument adapted to be influenced by one or another of said thermo-electric elements, a common distributor with switches and connections whereby the single control instrument is placed in operative relation with one or another of said thermo-electric elements and with the corresponding circuit controllers, and means whereby the action of each thermo-electric element on the control instrument may be varied relative to and independent of the action of each and every other thermo-electric element, and a variable resistance included in the circuit of each thermo-electric element.
10. In a control system, the combination of a plurality of heaters, a single electrical instrument connected to be successively controlled by the temperature of said heaters and comprising a pointer and means for controlling said heaters including two electric circuits having movable terminals separate from but dependent upon said pointer, means for periodically causing said pointer to selectively actuate said terminals to close said circuits, and means for varying the control exercised by each heater over said single electrical instrument independent of the control exercised by the other heaters.

In testimony whereof, I affix my signature.

HOWARD A. HANDS.
